UNITED STATES PATENT OFFICE.

ELIHU THOMSON, OF SWAMPSOFT, MASSACHUSETTS, ASSIGNOR TO GENERAL ELECTRIC COMPANY, A CORPORATION OF NEW YORK.

MAKE-AND-BREAK SPARKER FOR INTERNAL-COMBUSTION ENGINES.

1,010,987.

Specification of Letters Patent.

Patented Dec. 5, 1911.

Application filed August 17, 1907. Serial No. 388,979.

To all whom it may concern:

Be it known that I, ELIHU THOMSON, a citizen of the United States, residing at Swampscott, county of Essex, State of Massachusetts, have invented certain new and useful Improvements in Make-and-Break Sparkers for Internal-Combustion Engines, of which the following is a specification.

This invention relates to ignition apparatus for engines operated by explosive vapor, and its object is to improve the devices in which a spark is produced by the mechanical separation of two terminals of an electric circuit; commonly termed make-and-break sparkers. Although this type of sparker is recognized as the most reliable, so far as the positive production of the spark is concerned, yet in its ordinary operation there is always more or less difficulty in connecting the moving elements of the sparker, located inside the cylinder, with the engine shaft or other actuating mechanism outside the cylinder. There must be a packed joint of some kind at the point where the operating rod or rock-shaft passes through the cylinder wall or head, and such a joint, exposed as it is to the hot gases of explosion, is very liable to leak and give trouble. Another objection to this type of sparker is that any warping or changing of position of the levers, connecting rods and other parts when heated, is apt to change the adjustment and cause the spark either to come at the wrong time, or perhaps to fail entirely.

While the ordinary jump-spark plug is liable to become sooted up or burned out, yet it has this great convenience, viz., that it can be screwed firmly into the cylinder wall or head, forming a tight joint with no moving parts, and furthermore it can be readily inspected and replaced.

The object of my invention is to obviate the objections to the make-and-break sparkers and place it practically on a par, so far as convenience is concerned, with the jump-spark plug. By the construction I have designed, I am enabled also to apply a make-and-break sparkler to engines designed for a jump-spark plug.

To this end the invention consists in a plug adapted to be screwed into the ordinary tapped spark-plug hole in the cylinder, said plug containing a movable abut-

ment, preferably a flexible metal diaphragm insulated from the plug and carrying one of the two separable contacts by whose separation the spark is produced. The other contact is mounted on the plug which is grounded through the engine frame. The diaphragm normally lies in such a position as to close the contacts together, but when buckled inwardly, that is, in a direction toward the cylinder, by the application of force to its outer face, the movement of the diaphragm causes a separation of the two contacts and the production of a spark. Suitable devices are provided for imparting inward impulses to said diaphragm at the proper time in the cycle of the engine, said devices comprising preferably an intermittently operated abutment effecting a pulsating movement of a column of liquid resting on said diaphragm; all as herein-after set forth in detail.

In the accompanying drawings, Figure 1 is a diagrammatic representation of a four-cylinder internal combustion engine equipped with my sparking device; Fig. 2 is a sectional elevation of the impulse mechanism; Fig. 3 is a sectional elevation of one of the spark-plugs; Fig. 4 is a similar view of a modified spark-plug; Fig. 5 is a top plan view of the impulse mechanism; Fig. 6 is a perspective view of the timing mechanism or distributor; and Fig. 7 is a section on the line 7—7, Fig. 3, partly broken away.

Referring first to Figs. 3, 4 and 7, it will be seen that the spark-plug consists of a central portion containing a chamber and tubular portions extending in opposite directions from said body. For convenience of manufacture this structure is made in three parts, to wit, a body 1 having at one end a circular flange 2 and at the other end a central screw-threaded projection 3 of smaller diameter and preferably slightly tapered; a circular top 4 having its edge screw-threaded and provided with a central upright neck 5; and a ring or union 6 having internal screw-threads to mesh with those on the edge of the top, and an internal flange 7 to engage with the flange 2 on the body 1. The projection 3 is screwed into the tapped spark-plug hole in the cylinder in the usual manner, the body 1 being preferably made polygonal to receive a wrench for this purpose.

Between the body and the top is a space

or chamber in which is housed a flexible metal diaphragm 8, which is electrically insulated from the spark-plug by insulation 9 inclosing the edge of said diaphragm and 5 clamped between the body and the top by screwing up the ring 7, notches 10 being made in the periphery of said ring to receive a spanner wrench. Electrical connection can be made with the diaphragm by 10 means of a binding-post 11 which rises from the diaphragm through a hole in the top 4, from which it is insulated by a bushing 12 of insulation.

Projecting from the lower end of the 15 screw-threaded projection 3 is a lug 13 to which is secured a contact 14, preferably a silver or platinum pin. Coöperating therewith is a similar contact 15, carried at the lower end of a rod 16 which passes down 20 through a suitable passageway 17 in said body 1 and projection 3. The upper end of the rod is in operative relation to the diaphragm. Thus, for instance, it may be directly secured thereto, as shown in Fig. 4. 25 Or, again, it may be pivoted to a strip of metal 18 secured to the edge of the diaphragm, as shown in Fig. 3, and have a short arm 19, substantially at right angles to said rod, bearing against the under side 30 of said diaphragm at or near its center. In any event, the connection is such that the two contacts 14, 15 are normally closed, but when the diaphragm is buckled downward, the two contacts are briskly separated and a 35 spark is produced.

As the passageway 17 exposes the diaphragm to the full force of the explosion in the cylinder, I provide means for supporting it at that time, comprising preferably 40 a series of radial ribs 20 formed on the under side of the top 4, against which the upper surface of the diaphragm will abut when the explosion takes place. In its normal position, the diaphragm does not quite 45 touch the ribs, since to do so would short-circuit the contacts.

The circuit of the contacts should contain sufficient self-induction or have voltage 50 enough to produce a good spark upon the sudden opening of the contacts. The times of sending current through the contacts may be regulated, as usual, by a revolving timer, but the formation of the spark is effected by the bulging or buckling of the diaphragm. A great variety of mechanical devices for actuating the diaphragm may be 55 used, but I prefer to employ a column of inelastic fluid, such as oil, resting on the upper side of said diaphragm, impulses being 60 communicated to said column by some suitable means. I use an oil of high boiling point and of not too great viscosity. It completely fills the space above the diaphragm and also fills the pipe 21 which is connected 65 in the upper end of the neck 5 by a union 22.

The pipe is preferably made of flexible strong material, such as copper, and is of small bore, so that it may be dealt with as a wire would be.

The pipe 21 connects with a device for 70 producing sudden impulses in the fluid column. As illustrative of a suitable mechanism for this purpose, I have shown a movable abutment, such as a piston 23, working in a cylinder 24 to which said pipe is connected. The cylinder is preferably immersed in an oil tank 25, and at the upper 75 end of each stroke of the piston a port 26 is uncovered, admitting oil from the tank to supply any deficiency in the pipe due to 80 leaks or changes of volume arising from contraction or expansion. The port 26 also affords an escape for any gas bubbles which may exist.

The piston is pivotally connected to a 85 lever 27 fulcrumed at 28 in the tank and urged downward by a powerful spring 29, whose tension can be adjusted by a compression screw 29' tapped through the lid of the tank. The free end of the lever rests 90 upon a cam 30 mounted on a shaft 31 which passes out through the wall of the tank and is geared to the engine shaft 32 by gears 33, 34. The cam is so formed that it gradually raises the free end of the lever until upon 95 reaching a certain point the lever is released. During the lifting of the piston the oil fills the pipe, and when the lever is released the spring impels the piston downward very suddenly and gives a vigorous 100 impulse to the fluid in the pipe, thereby actuating the diaphragm and producing the spark. The timing of the spark can be controlled by timing the movements of the piston. This can be readily accomplished 105 by mounting the gear 34 on a sleeve 35 having an inclined slot 36 engaging with a pin 37 in the shaft 31. A grooved collar 38 on said sleeve is engaged by a fork 39 on a lever 40, whereby the sleeve can be slid lengthwise 110 on the shaft. In so doing, the pin and slot cause the shaft 31 to shift angularly with reference to the sleeve, and thus the relative adjustment of the engine shaft and the cam is altered, and the time of the spark 115 with reference to the revolution of the engine shaft can be varied. The lever 40 can be adjusted by means of a latch 41 and a notched quadrant 42.

When it is desired to apply my invention 120 to a multicylinder engine, instead of using a plurality of separate impulse devices, one for each cylinder, I prefer the arrangement shown in Figs. 1 and 6, where one impulse device and a single pipe are connected by 125 branch pipes with the several spark-plugs. The cam which operates the impulse device has a plurality of toes, one for each spark-plug; (or a single-toed cam can be run at a higher speed); and the several diaphragms 130

all respond simultaneously to every impulse sent through the pipe. But by means of a suitable distributor the current is sent to the spark-plugs in regular order, and only that 5 plug which has current at the instant the impulse reaches it can produce a spark. The distributor may consist of a revolving contact-arm 43 preferably mounted on the cam shaft 31 and making connection in sequence 10 with the several stationary contacts 44 from which conductors 44' are run to the several spark-plugs. A source of current, such as a battery 45, is in circuit with the contact-arm 43. The sleeve 35 which carries the 15 gear 34 may also carry the arm 43, so that the circuit to each spark-plug will be closed earlier or later in exact relation with the sparking mechanism.

It will be seen that this make-and-break 20 spark-plug can be easily removed for examination or replacement by another, it being only necessary to unscrew the union of the impulse pipe, and perhaps to disconnect the electric conductors. Or, if the electric connection 25 is retained and the impulse pipe is again connected to the plug after its removal from the cylinder, the engine can be started and the operation of the plug observed, and corrected if necessary before 30 returning it to its working position.

What I claim as new and desire to secure by Letters Patent of the United States, is,—

1. The combination with the cylinder of an internal combustion engine of a removable 35 spark-plug comprising a movable insulated abutment, sparking contacts controlled thereby, and means for imparting impulses to said abutment from a source outside of said cylinder.

40 2. The combination with the cylinder of an internal combustion engine of a removable spark-plug comprising relatively movable 45 sparking contacts, a movable insulated abutment in operative relation therewith for separating said contacts by a movement 50 toward the cylinder, and means for imparting such movement thereto from a source outside of said cylinder.

3. The combination with the cylinder of 55 an internal combustion engine of a removable spark-plug comprising relatively movable 60 sparking contacts, a movable insulated abutment in operative relation therewith for separating said contacts by a movement 65 toward the cylinder, a device for producing impulses at regular intervals of time, and means for communicating said impulses to the outside of said abutment.

4. The combination with the cylinder of 70 an internal combustion engine of a removable spark-plug comprising relatively movable 75 sparking contacts, a movable insulated abutment in operative relation therewith for separating said contacts by a movement 80 toward the cylinder, a cam revolving in syn-

chronism with said engine, a lever actuated by said cam, and means for imparting the impulses of said lever to the outside of said abutment.

5. The combination with the cylinder of 75 an internal combustion engine of a removable spark-plug comprising relatively movable 80 sparking contacts, a movable insulated abutment in operative relation therewith for separating said contacts by a movement 85 toward the cylinder, a column of fluid in contact with the outside of said abutment, and means for imparting impulses to said fluid column.

6. The combination with the cylinder of 90 an internal combustion engine of a removable spark-plug comprising relatively movable 95 sparking contacts, a movable insulated abutment in operative relation therewith for separating said contacts by a movement 100 toward the cylinder, a column of fluid resting on the outside of said abutment, and an intermittently operated piston for imparting impulses to said fluid column.

7. The combination with the cylinder of 95 an internal combustion engine of a removable spark-plug comprising relatively movable 105 sparking contacts, a movable insulated abutment in operative relation therewith for separating said contacts by a movement 110 toward the cylinder, an oil tank, a pump therein, a pipe connected to said pump with the outside of said abutment, and a cam for operating said pump.

8. The combination with a multicylinder 100 internal combustion engine, of a spark-plug for each cylinder comprising a movable 105 abutment and sparking contacts controlled thereby, a fluid-filled pipe having branches leading to the outside of said abutments, an impulse device driven by the engine and operating upon the fluid in said pipe, and means for distributing current to said spark-plugs.

9. The combination with a multicylinder 110 internal combustion engine, of a spark-plug for each cylinder comprising a movable 115 abutment and sparking contacts controlled thereby, a fluid-filled pipe having branches leading to the outside of said abutments, an impulse device driven by the engine and operating upon the fluid in said pipe, means for distributing current to said spark-plugs, and means for simultaneously timing the impulse device and the current distributor. 120

10. A make-and-break spark-plug comprising a body carrying a stationary contact, an insulated diaphragm housed in a chamber in said plug, a movable contact connected with said diaphragm, a tubular 125 neck for conveying impulses to the upper side of said diaphragm, a fluid and a device in operative relation thereto for imparting such impulses, and means for making electrical connection with said diaphragm. 130

11. A make-and-break spark-plug comprising a body adapted to screw into an engine cylinder, and containing a longitudinal passageway, a stationary contact on said body, a top having a tubular neck, a ring for uniting said body and top, an insulated diaphragm clamped between said body and top, a binding-post on said diaphragm insulated from said top, and a rod carrying 10 a movable contact and extending through said passageway, said rod being in operative relation to said diaphragm.

12. The combination with the cylinder of an internal combustion engine of a removable spark-plug comprising relatively movable sparking contacts, a movable insulated abutment in operative relation therewith for separating said contacts by a movement toward the cylinder, a column of fluid resting on the outside of said abutment, an intermittently operated piston for imparting impulses to said fluid column, and means for automatically maintaining the quantity of fluid in the column substantially constant.

13. The combination with the cylinder of an internal combustion engine of a removable spark-plug comprising relatively movable sparking contacts, a movable insulated 25 abutment in operative relation therewith

for separating said contacts by a movement toward the cylinder, a column of fluid resting on the outside of said abutment, a piston for imparting impulses to said fluid column, a casing surrounding the piston, fluid therein, and means for permitting a flow between the fluid in the casing and the fluid in the column.

14. The combination with the cylinder of an internal combustion engine of a removable spark-plug comprising relatively movable 40 sparking contacts, an abutment in operative relation therewith movable toward and away from the cylinder for separating said contacts by a movement toward the cylinder, a column of fluid resting on the outside of said abutment, a piston imparting impulses to said fluid column, a casing surrounding the piston, fluid therein, and a port in the piston open during a portion of 45 the stroke of the piston permitting a flow between the fluid in the casing and the fluid in the column.

In witness whereof, I have hereunto set my hand this fourteenth day of August, 55 1907.

ELIHU THOMSON.
